US00D702240S

(12) **United States Design Patent**
Lepp et al.

(10) **Patent No.:** US D702,240 S
(45) **Date of Patent:** ** Apr. 8, 2014

(54) **UICC APPARATUS**

(75) Inventors: **James Randolph Winter Lepp**, Ottawa (CA); **Jean-Philippe Paul Cormier**, Ottawa (CA); **Sheldon Terry Schwandt**, Wellesley (CA); **Oleg Los**, Buffalo Grove, IL (US); **Petra Braun**, Dormagen (DE)

(73) Assignee: **BlackBerry Limited**, Waterloo, Ontario

(**) Term: **14 Years**

(21) Appl. No.: **29/418,619**

(22) Filed: **Apr. 18, 2012**

Related U.S. Application Data

(63) Continuation of application No. 29/418,309, filed on Apr. 13, 2012.

(51) **LOC (10) Cl.** **14-02**

(52) **U.S. Cl.**

USPC **D14/436; D14/437**

(58) **Field of Classification Search**

(57) **CLAIM**

We claim the ornamental design for a UICC apparatus, as shown and described.

DESCRIPTION

FIG. 1 is a plan view of a UICC apparatus; FIG. 2 is a front view of the UICC apparatus of FIG. 1; FIG. 3 is a right side view of the UICC apparatus of FIG. 1; FIG. 4 is a left side view of the UICC apparatus of FIG. 1; FIG. 5 is a rear view of the UICC apparatus of FIG. 1; FIG. 6 is a plan view of a second embodiment of the UICC apparatus; FIG. 7 is a front view of the UICC apparatus of FIG. 6; FIG. 8 is a right side view of the UICC apparatus of FIG. 6; FIG. 9 is a left side view of the UICC apparatus of FIG. 6; and, FIG. 10 is a rear view of the UICC apparatus of FIG. 6. Broken lines and portions contained within broken lines are not claimed.

1 Claim, 2 Drawing Sheets
